KEY HOLDING ATTACHMENT FOR KEY CASES

Charles W. Elsenheimer, Meriden, Conn., assignor to
Prentice Corporation, Kensington, Conn., a corpora-
tion of Connecticut

Filed Jan. 15, 1969, Ser. No. 15,355

Term of patent 14 years

Int. Cl. D3—99

U.S. Cl. D87—8

FIG. 1

FIG. 2

FIG. 3

FIG. 4

FIG. 1 is a perspective view of a key holding attachment for a key case composed of a plurality of key holding members embodying the new design, one of the key holding members being shown swivelled in an upward position and the others being shown in their normal depending storing position; the back attachment plate being substantially plain with attachment holes near the base;

FIG. 2 is an enlarged side elevational view of one of the key holding members of FIG. 1, the hook member being broken away below the bottom of the holding member;

FIG. 3 is a front elevational view of FIG. 2 with the hook member shown in full;

FIG. 4 is a rear elevational view of FIG. 3; and

FIG. 5 is a bottom plan view of FIG. 2.

The characteristic feature of my new design resides in the particular figure 8 configuration of each key holding member which is formed of a single piece of flat material so that its ends are in overlapping relation at the back of the member, and so that the hook slot in each member extends from a point approximately midway of the bottom of such member upwardly and rearwardly to the overlapping end of such piece and is not observable in the front of the member.

I claim:

The ornamental design for a key holding attachment for key cases, as shown.
